(57) CLAIM

An ornamental design for a split-sole shoe with blue stripe and soles, as shown and described.

DESCRIPTION

The file of this patent contains at least one drawing executed in color. Copies of this patent with color drawing(s) will be provided by the Office upon request and payment of the necessary fee.

FIG. 1 is a perspective view of an embodiment of our new design of a split-sole shoe with blue stripe and soles;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1;

FIG. 7 is a back view of the design of FIG. 1;

FIG. 8 is another perspective view of the design of FIG. 1, the perspective view illustrating this embodiment when it is placed in a folded configuration;

FIG. 9 is a perspective view of a second embodiment of our new design of a split-sole shoe with blue stripe and soles, where the blue portions are indicated using the USPTO convention of horizontal lines for blue, such as Pantone PMS 3242-3278, PMS 2905-2995, and 7453C-7472C;

FIG. 10 is a first side view of the design of FIG. 9;

FIG. 11 is a second side view of the design of FIG. 9;

FIG. 12 is a top view of the design of FIG. 9;

FIG. 13 is a bottom view of the design of FIG. 9;

FIG. 14 is a front view of the design of FIG. 9;

FIG. 15 is a back view of the design of FIG. 9;

FIG. 16 is another perspective view of the design of FIG. 9, the perspective view illustrating this embodiment when it is placed in a folded configuration;

FIG. 17 is a perspective view of a third embodiment of our new design of a split-sole shoe with blue stripe and soles, where the blue portions are indicated using a checkered pattern to indicate the blue color Pantone 7466C;

FIG. 18 is a first side view of the design of FIG. 17;

FIG. 19 is a second side view of the design of FIG. 17;

FIG. 20 is a top view of the design of FIG. 17;

FIG. 21 is a bottom view of the design of FIG. 17;

FIG. 22 is a front view of the design of FIG. 17;

FIG. 23 is a back view of the design of FIG. 17; and,

FIG. 24 is another perspective view of the design of FIG. 17, the perspective view illustrating this embodiment when it is placed in a folded configuration.
